UNITED STATES PATENT OFFICE.

JACQUES SCHNEIDER AND FREDERIC BILLON, OF SOLOTHURN, AND ERNST HURLIMANN, OF ZUCHWIL, SWITZERLAND, ASSIGNEES TO THE FIRM "SCINTILLA," OF SOLOTHURN, SWITZERLAND.

DISTRIBUTOR FOR THE HIGH-VOLTAGE CURRENT OF MAGNETO-ELECTRIC IGNITION MACHINES.

Application filed August 22, 1919. Serial No. 319,233.

To all whom it may concern:

Be it known that we, JACQUES SCHNEIDER, a citizen of the Swiss Republic, residing at Solothurn, Switzerland, FREDERIC BILLON, a citizen of the Swiss Republic, residing at Solothurn, Switzerland, and ERNST HURLIMANN, a citizen of the Swiss Republic, residing at Zuchwil (Canton Solothurn), Switzerland, have invented certain new and useful Improvements in Distributors for the High-Voltage Current of Magneto-Electric Ignition Machines, of which the following is a specification.

In magneto-electric ignition machines for internal combustion engines, the distributor serves as is well known for distributing the high voltage current at the proper times to the sparking plugs arranged in the several engine cylinders.

The improved construction of a distributor according to the present invention is characterized by the feature that the conducting distributor segments that are connected electrically to one another, as well as the centrally situated current-supply contact, are cast in the insulating material of the distributor body and rotate therewith.

A constructional form of an improved distributor according to the present invention is illustrated in the accompanying drawings, in which:—

Figure 1 shows the distributor in section along the axis, and

Figure 2 a section perpendicular to the axis.

The two metal distributor segments *a* and *b*, (which are staggered axially as well as circumferentially), and the central current-supply contact *c* are cast in the distributor body *d* which has a cylindrical form and is made of insulating material. All these parts are formed with projecting extensions for the purpose of preventing their becoming loose. They are previously connected electrically together by means of the wire *e*.

The distributor cylinder *d* is driven by the ring of teeth *f* which is fixed by means of a split ring *g* to a disc-shaped extension *h* (centered in the ring of teeth) of the cylinder *d* and which drives the cylinder by means of a stud or screw *i* projecting into the latter.

It is of special importance in the present device to have the whole distributor organ, i. e. both lead-in and lead-out conductors, on one and the same side of the toothed sector *f* and further that the sliding contacts *a* and *b* shall lie in different planes perpendicular to the axis.

What we claim is:—

A distributor for the high voltage current of a magneto-electric machine including a toothed wheel of hollow form, a solid cylindrical body of insulating material projecting from one side only of said wheel and having a flange formed thereon fitting into the toothed wheel, means including a split spring ring coacting with a groove formed in the hollow toothed wheel and the flange of the cylindrical body to prevent relative longitudinal movement of the wheel and the cylindrical body, means including a set pin for preventing relative rotational movement of the toothed wheel and the cylindrical body, a contact stud imbedded in the center of the outer end of the cylindrical body remote from the flange, two contact segments embedded in the curved side of the cylindrical body and arranged in parallel planes perpendicular to the axis of the body, and electrical connecting means between said contact stud and said contact segments, said segments being relatively displaced on the circumference of the cylindrical body.

In testimony whereof we have signed our names to this specification.

JACQUES SCHNEIDER.
ERNST HURLIMANN.
FREDERIC BILLON.
